UNITED STATES PATENT OFFICE.

HENRY FAIRBANKS, OF ST. JOHNSBURY, VERMONT.

IMPROVEMENT IN AUTOMATIC GRAIN-WEIGHING SCALES.

Specification forming part of Letters Patent No. 92,436, dated July 13, 1869.

To all whom it may concern:

Be it known that I, HENRY FAIRBANKS, of St. Johnsbury, in the county of Caledonia, in the State of Vermont, have invented certain new and useful Improvements in Scales for Weighing Grain, applicable also to the weighing of analogous material; and I do hereby declare that the following is a full and exact description thereof.

I will first describe what I consider the best means of carrying out my invention, and will afterward designate the points which I believe to be new therein.

The accompanying drawings form a part of this specification.

Figure 1 is a side elevation, partly in section, showing the scale-beam and the provisions for changing at each oscillation of the latter the position of the spout which leads the grain into the separate bin. Fig. 2 is a corresponding end view. Fig. 3 is a plan view of the same parts, with the cover or boxing of the delicate parts removed. In these figures the weighing-beam is in its lowest position. Fig. 4 is a section corresponding to Fig. 1, but with the beam in its highest position. Fig. 5 is a cross-section, showing the parts in the position assumed in Fig. 4. Fig. 6 is a perspective view of the entire machine on a smaller scale.

Similar letters of reference indicate corresponding parts in all the figures.

The drawings represent the novel parts with so much of the ordinary parts as seems necessary to indicate their relations thereto.

The parts not represented may be made in any approved manner.

I prefer the several modifications of the form ordinarily adopted in our manufacture, and known as the "Fairbanks patent scales."

A is a rigid frame-work, which supports the several parts, and A' is a box, made of wood or other suitable material, removable at will, the function of which is simply to cover and protect the several parts from accident and derangement.

B is the scale-beam, graduated as usual, and carrying a movable poise, b, which may, if desired, be rigidly set at any desired point by the aid of a set-screw or other ordinary device. The several knife-edges on this beam, the hang-

er or support A², bolted upon the frame A, the connections W to the loaded platform below, and the provisions for attaching a permanent weight at the other end of the beam to balance the platform will be readily understood without explanation.

I will describe minutely only the parts in which the novelty lies.

The arm B' extends upward from near the end of the lever B, and carries a cross-pin, b', playing freely up and down through a hole in the frame-work A as the beam B is tilted in one direction or the other. A long and slender spring, C, presses upward against this pin b', and moves up and down therewith, as represented. The spring C is riveted or otherwise secured to the other side of the lever D, which turns in bearings d on the upper side of the frame-work A. This lever has a notch, as represented, at the point d', adapted to receive a sharp corner or angle carried upon the upper end of the arm E, which will be described farther on. The lever D extends over the pin b', so that as the scale-beam B rises it lifts the lever D by means of the pin b'. The arm E is carried on a cross-shaft or axis, e, which is supported in bearings a little above the frame-work A. This shaft e carries also two other arms, with which it is connected, (marked respectively E' and E².) The shaft e and its connected arms rock or oscillate at each operation of weighing, and the arms E' and E² are alternately depressed through liberal openings provided in the frame-work A, as represented. The arm E' extends under the cross-pin b', and is depressed thereby at proper times. The arm E² carries a weight, E³, the gravity of which is sufficient to cause the shaft e and its attachments to turn with considerable force.

M' and M², Fig. 6, are two spacious compartments or bins, into one or the other of which the grain is constantly received and is alternately discharged. The discharging operation is sudden and by ordinary means, which need not be described. The receiving is more gradual, the grain being received in a stream of moderate size through the movable spout N. The grain is supplied into this spout from above through an ordinary spout, which is in

line, or nearly in line, with the supporting-shaft n of the spout N , and need not be particularly described.

Supposing the beam B to be balanced—or, in other words, that a weighing has just been effected—and that the grain has just been deflected from the filled bin to the other empty one, and the grain from the filled bin has just been discharged into a bag or other receptacle, (not represented,) the reduced weight on the platform will allow the scale-beam, with its arm B' , to sink into the position shown in Fig. 1. In thus sinking, the cross-pin b' descends with sufficient force not only to overcome the slight tension of the spring C , but also to act against the arm E' with sufficient force to tilt the shaft e and its appurtenances, and to elevate the weight E^3 until the corner or angle at the top of the arm E enters the notch d' in the lever D . The parts remain in this condition until, by the accumulation of the grain in the bin, the beam B is raised. The force of the spring C assists the lever B in commencing to rise and until it comes into the position for weighing correctly. It gradually diminishes its force in lifting the beam B , and at the same time loses the force with which it correspondingly depresses the lever D , to which it is bolted, until the bin having been filled to the proper weight, the beam B leaves the spring C entirely and, rising higher, touches the under side of the notched lever D . The notch d' and the corresponding corner or angular piece carried on the arm E , which enters this notch, are accurately shaped and smooth, so that the lever D , having been relieved from the depressing force of the spring C , is lifted by a very slight touch against its under surface. This slight touch it receives from the cross-pin b' , and instantly the lever D is thrown up and the arm E released. The shaft e and its attachments are now turned with considerable force by the gravity of the weight E^3 . The turning of this shaft and its attachments effects the required change of position of the discharging-spout N , turning it first in one direction to empty it into one bin and then in the other direction to empty it into the other bin. The turning of this discharging-spout in the opposite directions is effected alternately by precisely similar motions of the beam B and its connections, and of the lever D , and of the shaft e and its connections. At one ascent of the beam B it liberates the arm E , and the descent of the weight E^3 shifts the spout N in one direction, and at the next ascent of the beam B the position of the spout N is shifted in the opposite direction. The means of effecting this is as follows:

To the arm E is connected a rod, G , which extends along nearly to the shaft n and is forked, as represented. (See the plan view, Fig. 3.) A cross-bar, G' , extending across between the forked arms rides on a central fixture or ridge, A^3 , which is so formed and arranged relatively to the fork G and the cross-

bar G' that as the latter is moved horizontally with considerable violence by the sudden descent of the weight E^3 it rests during the first part of its motion on the plain upper surface of the frame-work A , but during the middle or latter portion of its motion it is lifted by the central fixture, A^3 . Now the forked piece G is free to tilt on this central piece, A^3 . In other words, it can allow either end of the fork to remain down and allow the other end to rise up at pleasure. Either end of the arms or forks $g' g^2$ is adapted to catch hold of and operate a corresponding arm, $n' n^2$, fixed on the upright shaft n . These arms $n' n^2$, being in fact parts of a single straight cross-bar fixed on the upright shaft n , and running close to the upper surface of the frame-work A , are alternately caught and turned by the fork $g' g^2$. There are pins or stops $A^4 A^5$, which prevent the arms $n' n^2$ from turning farther than is desired. At each thrust of the piece G one of the forks $g' g^2$ catches the corresponding arm, $n' n^2$. So soon as it is firmly engaged therewith, so that it cannot rise, the incline plane, which I have termed the "central fixture, A^3 ," tries to lift the entire forked piece, but not being able to do this by reason of the engagement of one fork, it tilts the forked piece, lifting the other fork-arm, so that it is of no effect. This construction and combination is peculiar and may deserve minute description. Supposing the parts to be in the position represented in strong lines in Fig. 3, the descent of the weight E^3 , and the corresponding vigorous thrust of the forked piece $g' g^2$, results, first, in the engagement of the arm or fork g' with the arm n' ; next, in suddenly turning the upright shaft n and the attached grain-spout N into the position indicated in dotted red lines, it having previously been in the position shown in dotted black lines, and meantime in the tilting of the forked piece $g' g^2$ by reason of the riding up of the attached cross-bar G' upon the incline A^3 , so that the other arm, g^2 , has no effect on the arm n^2 , but passes idly over it. Now, on the return of the forked piece $g' g^2$ with its attached cross-bar G' , and the repetition of the thrust, the other arm, g^2 , first engages, and after it has got hold of and locked under the corresponding arm, n^2 , the lifting of the forked piece at the center by means of the incline A^3 now tilts the forked piece $g' g^2$ to the opposite side, so that the arm g' is now lifted and passes idly over without engaging with the arm n' .

It will be seen that the ends of the forks $g' g^2$ are adapted to not only strike against the arms $n' n^2$, but to hook under them, so as to effectually resist any tendency to disengage by lifting.

The means above described are sufficient for changing the position of the spout N and its attachments, but they fail to provide against the force of the current of grain, or any other cause which might in the interim disturb the position of the parts. To guard against any

such accident I have provided the spring-catches $H' H^2$, which are secured on a fixed cross-piece, A^6 , and are adapted to receive the ends of the arms $n' n^2$ in notches $h' h^2$. The arms n' or n^2 next to be operated upon is held in the corresponding notch, h' or h^2 , with considerable force, sufficient to resist any slight tendency of the parts to change their positions. At each thrust of the forked piece G and its attachments the arm on which it acts is not only caught by the proper forked piece, but is detached or liberated from the catch. The liberation of the arm is not effected antecedent to the engaging of the fork therewith, but the whole operation is nearly instantaneous. In short, at each thrust of the rod G one of the arms of the forked piece $g' g^2$ (in the position shown in Fig. 3) first engages with the corresponding spring-catch, H' , and deflects it outward so as to release the arm n' . It next turns the connected grain-spout N until the arm n' is quite over against the stop A^4 , and the other arm, n^2 , is in its proper position for the next operation, and is held by the corresponding spring-catch, H^2 . After having thus performed all that is required for its complete operation, it returns by the descent of the scale-beam B and the turning of the shaft e and its connections, and remains quiescent until its bin is full and the notched lever D is again lifted, when the operation is repeated to turn the grain-spout N in the opposite position.

A spring may be employed with some success in place of the weight E^3 , to exert a constant and sufficient force to turn the shaft e ; but I prefer the weight, as represented.

I claim as my improvement in scales and desire to secure by Letters Patent—

1. The arm or extension B' , with the cross-pin b' , or an equivalent laterally-extended surface near the top, adapted to alternately lift

the notched lever D , and to depress the rocking lever E' and its connections at each weighing operation, substantially as and for the purposes herein set forth.

2. The weighted lever $E E' E^2$ and the connected weight or constant force E^3 , arranged to be set by the depression of the beam B , to be held by the lever D , and ultimately released by the rising of the beam B , and to turn forcibly on such release, substantially as and for the purposes herein set forth.

3. The spring C , arranged as represented, and adapted to carry up the scale-beam to the position for weighing correctly, and also to hold down the notched lever D with a force graduated in accordance with the amount of depression of the scale-beam, as and for the purpose described.

4. The thrusting-piece $G g' g^2$, with its cross-bar G' , or its equivalent, constructed and arranged as represented, and adapted to operate relatively to the arms $n' n^2$, which operate the grain-spout N , substantially in the manner and for the purpose herein set forth.

5. The combination and the arrangement of the thrusting part $g' g^2$, deflecting or tilting ridge A^3 , arms $n' n^2$ with the notched lever $D d'$, rocking lever $E E' E^2$, and scale-beam $B b'$, all adapted for joint operation substantially in the manner and with the effect herein set forth.

6. The spring-catches $H' h' H^2 h^2$, arranged relatively to the arms $n' n^2$ and to the forks $g' g^2$, substantially as and for the purposes herein set forth.

In testimony whereof I have hereunto set my name in presence of two subscribing witnesses.

HENRY FAIRBANKS.
